CLAIM

I claim the ornamental design for a feeding platter for pets, as shown and described.

DESCRIPTION

FIG. 1 is a top view of a feeding platter for pets;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom view thereof; and,

FIG. 7 is an isometric view thereof.

The characteristic feature of the design resides in the shape of the object as defined by its periphery; by the indentations or reliefs in the top surface of the object; and the textured top surface.

The article in which the design is embodied is intended to be used for attracting and feeding domestic pets such as dogs and cats.
